UNITED STATES PATENT OFFICE.

FREDERICK SIEMENS, OF DRESDEN, GERMANY.

GAS-FURNACE.

SPECIFICATION forming part of Letters Patent No. 486,540, dated November 22, 1892.

Application filed March 26, 1886. Serial No. 196,675. (No model.) Patented in England December 8, 1883, No. 5,677; in France December 21, 1883, No. 159,316; in Belgium December 22, 1883, No. 63,626; in Germany January 22, 1884, No. 31,113, and in Austria-Hungary June 26, 1884, No. 10,258 and No. 26,486.

To all whom it may concern:

Be it known that I, FREDERICK SIEMENS, a subject of the Emperor of Germany, residing at Dresden, Saxony, in the German Empire, have invented certain new and useful Improvements in Gas-Furnaces, (for which I have obtained Letters Patent in Great Britain, dated December 8, 1883, No. 5,677; in France, dated December 21, 1883, No. 159,316; in Belgium, dated December 22, 1883, No. 63,626; in Germany, dated January 22, 1884, No. 31,113, and in Austria-Hungary, dated June 26, 1884, No. 10,258 and No. 26,486,) of which the following is a specification.

15 My invention relates to that class of regenerative gas-furnaces used for high temperatures, such as steel-melting on the open hearth and in crucibles, glass-melting, heating iron and steel, and for other purposes, 20 which are constructed with four regenerators acting in pairs and alternately, one pair serving for heating separately the gaseous fuel and air supplying the heating-chamber, while the other pair serves for storing heat from 25 the products of combustion on their way from the said heating-chamber to the chimney-stack, the direction of the inflowing and outflowing currents being reversed from time to time. For such furnaces and their application to various purposes in the arts my brother, the late Sir William Siemens, and myself, sometimes cojointly and sometimes independently, have obtained Letters Patent in the United States and in other countries,

35 and their general construction and action are now so well known that it will be unnecessary for me to give a full description thereof in this specification, in which I confine myself mainly to their construction and working in 40 so far as they are affected by my present improvement. In these furnaces as they have been heretofore constructed and worked the flame has been directed on and caused to strike the objects or materials that are to be heated. This method of working by the chemical action of the substances in combination or by the mechanical action of solid particles carried with the flame often seriously damages the materials acted on and the

crucibles, pots, or other vessels containing 50 them, as well as the walls of the furnace itself. Moreover, when the flame impinges on objects colder than itself or obstructing it, the combustion is rendered imperfect, and consequently there is considerable waste of fuel. 55

My invention has for its object to avoid these evils by so constructing and working furnaces that the flame is kept entirely clear from the objects or materials that are to be heated and from the furnace-walls, and that 60 the whole of the heat is obtained by radiation from the flame itself and from the roof and walls of the furnace-chamber, which are heated by radiation from it. Furnaces operating in this manner may be of various 65 forms. They may have chambers of considerable length vaulted over, with the flame passing along their upper part from end to end, or they may be of circular, semicircular, horseshoe, or other forms, such that the combustible 70 gases enter by an opening or openings and sweep across or around the chamber and products of combustion issue by an opening or openings conveniently placed for that purpose. The object is to get a flame moving 75 slowly in a line which keeps it as clear as possible from the walls, roof, and bed of the furnace-chamber. The slow movement of the flame is of advantage in preventing the agitation of the dust or other fine particles 80 and the injurious effects of these or of the flame itself on the furnace-walls and the materials acted on.

In order to effect these results, my invention consists in a furnace so constructed that 85 the flame will traverse only the upper part of the furnace-chamber and keep entirely clear from the objects and materials that are to be heated and from the furnace-walls and so that the materials will be heated by radiation from 90 the flame itself and from the roof and walls of the furnace-chamber.

My invention also consists in a furnace having the heating-chamber constructed with a high crown and ports placed at such a 95 height as to keep the flame above the working holes or doors of the furnace.

It further consists in the arrangement of

the gas and air ports at the upper part of the walls of the heating-chamber for the purpose of directing the flame in such a direction that it will touch neither the materials to be heated or melted in such chamber nor, as far as possible, the surrounding walls thereof, in order that an undisturbed combustion may be secured, and that at the same time the surrounding walls and the material in the furnace-chamber may be protected from the injurious direct action of the flame.

The accompanying drawings in which corresponding parts are designated by similar letters, represent various constructions of furnaces as examples, showing how my invention may be carried out in practice under various conditions; but it is to be understood that I do not limit myself to the various forms of furnaces herein described, and that some of them shown as applied to certain purposes may also be used for other purposes, whether mentioned or not in this specification.

Figure 1 is a longitudinal section of a furnace for melting glass in pots, illustrating the application of my invention to a furnace in many respects similar in construction to that described in Letters Patent of the United States No. 256,748, heretofore granted to me. Fig. 2 is a sectional plan on the line X X of Fig. 1. Fig. 3 is a transverse section on the line Y Y of Fig. 1. Fig. 4 is a longitudinal section of a crucible steel-melting furnace having my improvement applied thereto, and Figs. 5 and 6 are transverse sections on the lines x x and y y, respectively. Fig. 7 is a longitudinal section of a glass tank-furnace of a horseshoe form, somewhat similar in construction to those for which Letters Patent of the United States, Nos. 229,846 and 230,668, have been heretofore granted to Sir William Siemens. Fig. 8 is a part-sectional plan taken on the line x' x' of Fig. 7. Figs. 9, 10, and 11 are respectively a longitudinal section, a transverse section on the line z z, Fig. 9, and a sectional plan on the line y' y', Fig. 9, of another horseshoe furnace for melting glass in pots. Fig. 12 is a longitudinal section, and Fig. 13 is a sectional plan, of an open-hearth steel-melting furnace of horseshoe form. Fig. 14 is a longitudinal section, and Fig. 15 is a sectional plan, of an open-hearth steel-melting furnace of rectangular form, showing different arrangements of gas and air ports on each side. Fig. 16 is a longitudinal section of a reheating or annealing furnace.

In all the figures, R are the regenerators, G the gas-flues, and L the air-flues leading into the furnace-chamber from the regenerators and acting alternately for supplying from one set of regenerators the heated gas and air to form the furnace-flame and to convey the hot products of combustion to the other set of regenerators.

C is the roof of the furnace-chamber.

O are working doors or gathering-holes, or

in the case of the crucible steel-furnaces are removable covers for giving access to the heating-chambers.

The gas and air ports, instead of being arranged so that the flame can impinge on the pots, crucibles, or materials in the tank or on the bed of the furnace, are at such height that the flame shall pass clear of the objects to be heated, and when these are pots or crucibles, lumps or packets of metal, or other material they are placed sufficiently far apart to allow free access of the radiated heat to all parts of them.

In order to prevent the flame of a furnace from coming into contact with the materials to be heated therein, various constructions may be adopted. For instance, the gas and air forming the flame may be introduced into the heating-chambers by openings of such form as to impart to the flame a horizontal motion across the furnace-chamber either from end to end or from side to side, or, in case of a horseshoe flame, from the inlets to the outlets on the same side or wall, the flame openings or ports to be located so that their point of delivery into the heating-chamber shall be above the height of the material to be heated, and the top and bottom walls may be horizontal for some distance, as shown in Figs. 1, 4, 9, 12, 14, and 16, or these walls may be inclined and converge toward each other, as shown in Fig. 7. It is also to be understood that I prefer the flame to move in the heating-chamber of the furnace above the doors, giving access thereto either for the introduction of fresh materials, watching the operation therein, or for withdrawing substances therefrom, as shown in all the figures except those representing the crucible steel-melting furnace, Fig. 6, in which the covers O also form the roof of the heating-chamber.

In order to prevent contact of the flame with the surrounding walls or roof of the heating-chamber of a furnace, a free space should be allowed for the development of the flame within it. For this purpose the gas and air ports should open into the heating-chamber at some distance from the side walls, as shown in the figures, and I prefer that the air port or ports be placed at the top of or at a higher level than the gas port or ports where practicable, and also that the air-ports when placed immediately above the gas-ports should be wider than the latter or overlap them, particularly on the side nearest the side wall of heating-chamber, as shown in Figs. 7, 8, 9, 10, 11, 12, 13, 14, and 15, (on right-hand side,) and in cases where the gas and air are delivered in adjoining streams I prefer that the air-ports should be located nearer to the side walls and the roof of the heating-chamber than the gas-inlets, as shown in Figs. 4, 5, 14, and 15. (Left-hand side.)

It is not possible to give dimensions of the distances for placing the gas and air ports from the roof or walls of the heating-chamber of a furnace, as they may be varied con-

siderably, according to the form of heating-chambers required and the arrangement of ports adopted. In some cases, although I should not select them by preference, it may be necessary to construct the heating-chamber of a furnace of such form, height, or width that the flame-ports cannot be kept entirely away from the roof or side walls, and in such cases it will be all the more necessary to place the air-ports nearest to the roof and side walls for the reason that the air-supporting combustion is not so much affected by contact with solid substances as the gas.

The number and form of gas and air delivery ports into the heating-chamber of a furnace may be varied considerably, as shown by the drawings annexed hereto; but it is understood that where a long travel is to be provided for the flame the gas and air should by preference be delivered into the furnace by one port for gas and one for air, as shown in Figs. 7, 9, 10, and 12, and these ports should be made high, so as to introduce thick volumes of gas and air, which will require time to burn thoroughly. When the length of travel for the flame is shorter and the same form or port is adopted, the gas and air ports are to be made less in height, but broader than in the former case, or the combustion may be promoted by causing ignition to commence inside the flame-ports, as shown in Fig. 14, (right-hand side,) or the gas and air may be delivered into the furnace in several adjoining streams, meeting in the heating-chamber, as shown in Figs. 14 and 15, (left-hand side,) or, again, these streams may be made to ignite before entering the heating-chamber, as shown in Figs. 5 and 16.

In the crucible steel-melting furnace shown by Figs. 4, 5, and 6, as the length of travel of the flame is comparatively short, the gas is brought into the chamber by two ports having an air-port between them and additional air-ports on either side, the ignition commencing as soon as the gas and air, which are delivered in thin streams, reach the height of a mixing-chamber, from which the flame issues into the wider heating-chamber of the furnace, across which it travels from end to end. A mixing-chamber for flame is shown in Figs. 1, 3, 7, 8, and 14 (right-hand side) and Fig. 16 in connection with other forms of furnace.

As shown by Fig. 13, in some cases the gas-ports may be formed so as to deliver the inflowing gas within the heating-chamber with an inclination toward its center and the air-ports may be arranged so as to deliver the inflowing air with an inclination toward its surrounding walls, with the view of keeping the gas away from the latter.

It is to be clearly understood that in the various forms of furnaces above described the principal object aimed at is to prevent contact of the actual flame with any surface or object that is stationary or is cooler than itself, as such contact interferes with the completeness of the combustion, and consequently

reduces its heat-radiating power, and at the same time to protect the surrounding walls and the material in the furnace-chamber. When the flame ceases, the products of combustion, though not visible as flame, retain, nevertheless, a large amount of heat, and the combustion having been completed when that condition is reached, these products are employed to heat surfaces or objects by actual contact with them, as the bricks of the flues leading to the regenerators and the regenerators themselves of the furnace.

A furnace-chamber constructed according to my invention acts like a muffle, with this difference, that the latter is heated from the outside, while the former is heated from the inside by direct radiation from the flame passing over the materials to be heated and the radiation from the furnace-walls.

Having thus described my invention, I claim and desire to secure by Letters Patent of the United States—

1. In a regenerative gas-furnace, the combination, with a heating-chamber provided with a high crown, of gas and air flues in the walls of said chamber and ports for conveying the gas and air into the furnace and the products of combustion therefrom, said ports formed substantially as herein set forth and described and located in the upper portion of the walls of said chamber near to the crown, whereby the resultant flame delivered into the furnace-chamber may be freely developed therein and not impinge upon the inner surface thereof or on the materials on the bed or bench.

2. In a regenerative gas-furnace, the combination, with a heating-chamber provided with a high crown, of gas and air flues, mixing-chambers, to each of which a pair of gas and air flues are connected, and a port-opening for each of said mixing-chambers, said ports formed substantially as herein set forth and described and located in the upper portion of the walls of said chamber near to the crown, whereby the gas and air are mixed prior to their entrance into the chamber, the resultant flame freely developed therein and not impinging upon the inner surface thereof or on the materials on the bed or bench.

3. In a regenerative gas-furnace, the combination, with a heating-chamber provided with a high crown, of gas and air flues, said air-flues located nearer to the side walls and crown of said chamber than the gas-flues, and ports for separately conveying the gas and air into the furnace, said ports formed substantially as herein set forth and described and located one above the other in the upper portion of said chamber near to the crown, whereby by reason of the greater specific gravity of the air discharged above the gas the resultant flame will be permitted to freely develop within the chamber and not impinge upon the inner surface thereof or on the materials on the bed or bench.

4. In a regenerative gas-furnace, the com-

bination, with a heating-chamber provided with a high crown, of two pairs of gas and air flues in the end wall of said chamber and ports for conveying the gas and air into the furnace and the products of combustion therefrom, said ports formed substantially as herein set forth and described and located in the upper portion of the end wall of said chamber near to the crown, whereby the resultant flame shall alternately horizontally enter the chamber from a pair of gas and air flues, be freely developed therein, sweep around the heating-chamber without touching the walls, roof, or materials therein, and leave the chamber by the other pair of flues, as described.

5. In a metallurgical furnace, the combination, with a heating-chamber provided with a

high crown, of ports for conveying gaseous fuel into the furnace and the products of combustion therefrom, said ports formed substantially as herein set forth and described and located in the upper portion of the walls of said chamber near to the crown, whereby the resultant flame will be delivered into the furnace-chamber and freely developed therein without being brought in contact with the inner surface of the furnace-chamber or material on the bed or bench thereof.

In testimony whereof I affix my signature in presence of two witnesses.

FREDERICK SIEMENS.
